FIG. 6.

Inventor:

Peter N. Mancuso

UNITED STATES PATENT OFFICE

PETER N. MANCUSO, OF HOLLYWOOD, CALIFORNIA

MOP WRINGING APPARATUS

Application filed October 16, 1928. Serial No. 312,924.

This invention relates to improvements in mop wringing apparatus and more particularly to a simple, efficient and inexpensive device of this character.

5 One of the objects of this invention is to provide a mop wringer with manually controlled means for actuating a movable squeezing jaw for the purpose of expressing the dirty water from the mop material.

10 Another object of this invention is to provide a tub or bucket with two compartments, one designed for clean water and the other designed for dirty water, so that the mop wringer may be secured over the dirty water compartment.

15 A further object of this invention is to provide a frame or housing in which there is a fixed and a movable jaw, constituting the main working parts of the mop wringer, the device being so designed as to facilitate the introduction of the mop material prior to expressing the dirty water therefrom.

20 A still further object of this invention is to provide the fixed and movable jaws of this invention in the form of two perforated plates to allow for the water expressed out of the device to escape into the proper compartment of the tub or bucket.

25 Another object of this invention is to provide cams for urging the movable jaw forwardly in the direction of the fixed jaw for closing the movable jaw against the mop material and thereby effecting the removal of the dirty water.

30 A still further object of this invention is to provide lever handles for actuating the cams or pushers which parts bear at all times against the movable jaw for the purpose of closing the movable jaw upon the fixed jaw.

35 A further object of this invention is to provide resilient means for normally holding a lever-like movable jaw in diagonal open position for the purpose of restoring the movable jaw to open position after the

same shall have been urged to closed position against the tension of said spring.

With the above and other objects in view my invention consists in the combination, arrangement and details of construction disclosed in the drawings and specification, and then more particularly pointed out in the appended claims.

In the drawings, wherein similar reference characters designate similar parts throughout the several views,

Figure 1 is an end elevation of this invention,

Figure 2 is a top plan view thereof,

Figure 3 is a vertical elevation of the movable jaw itself,

Figure 4 is a fragmental top plan view, differing from Figure 2 in that the movable jaw is in Fig. 2 shown in closed position,

Figure 5 is a side elevation of my invention, and

Figure 6 is a vertical sectional fragmental elevation showing the movable jaw in open position.

Referring to the drawings, which are merely illustrative of my invention 10 designates a tub having an intermediate vertical partition 14 arranged therein and extending downwardly to join the tub bottom 13. The partition 14 divides the tub into two compartments, one designated A and the other designated B, the compartment A being reserved for dirty water while the compartment B is reserved for clean water.

The parts of the mop wringer will now be described. 15 designates a hook formed upon the upper curled edge of a perforated fixed plate 16 which is spaced parallel to the wall 17 forming a cross wall of a channel shaped housing or frame for the mop wringer, this wall 17 being operatively secured upon the partition wall in any desir-

able manner so as to practically form an extension of this partition wall.

Between the imperforate wall 17 and the parallel spaced perforate plate 16 is a thru passage 18 thru which the dirty water expressed from the mop material and finding its way thru the ports 18a of the perforated plate 16 may escape downwardly into the dirty water compartment A of the tub. In this way it is readily seen that access is given the dirty water to find an easy path back into the tub.

The upper and lower ends of the wall 17 are designed to have spacer members for spacing the perforated plate alongside of the fixed plate 17. The side walls or right-angularly disposed flanges 22, 22a are formed upon the cross wall 17 to guide the movable jaw. The movable jaw is made in the form of a perforated plate 19 having the ports 20 for the escape therethru of dirty water and this movable jaw or perforated plate is lever-like pivoted at its lower end adjacent to the lower part of the perforated fixed plate 16 upon a shaft 23 extending transversely of the mop wringer housing so as to join together the side flanges 22, 22a. A coiled spring 36 is operatively wound around this shaft 21 so that one end is secured rigidly upon the shaft 23 and the other end secured operatively to the movable jaw 19. This spring will normally hold the movable jaw in a diagonal open position with respect to the fixed wall 16, to allow the mop material to be introduced into the boxing formed by the wall 16, the side flanges 22, 22a and the movable jaw 19; when the movable jaw is thus held in open position the upper part of this frame will be wider than the lower part until as the lower part of the receptacle thus formed is reached, the narrowest width of the device is found.

For the purpose of actuating the movable jaw 19 to open and particularly to close suitable mechanism is provided. A cross shaft 21 also secured at its opposite ends in the side flanges 22, 22a is connected at its opposite ends to the curved-crank-like terminals 33 of the lever handles 31 extending so as to flank said side flanges, there being a cross rod serving as a handle 34 connecting both handles 31. Upon the shaft 21, fixedly secured thereupon, are a plurality of pushers 25 having upper bifurcated portions 30 in which are disposed pins 29 upon which are trunnioned or journaled rollers 28 constrained to bear at all times upon and against the movable jaw 19. The coiled spring 36 has the effect not only to hold the movable jaw 19 in normally open position but to hold the handles 31 in upright position as well.

23a designates a cross rod or rung secured so as to brace together the side walls of the

entire device. It will be seen that the side flanges or side walls may be perforated if desired as at 24, so that all sides of the receptacle into which the mop material fits to have its dirty water expressed therefrom may also be formed with ports. 33 designates brush supports secured upon the front face of the wall 17.

In operation the person takes hold of the handle of the mop and inserts the mop material directly into the receptacle so that the mop material goes down as far therewith as is convenient. The operator then takes hold of the handle 34 draws downwardly the levers 31 and in doing so causes the pusher terminals 33 of the lever handles to turn the shaft 21 in a clockwise direction in Figure 6; this will cause the pushers 25 to simultaneously push the movable perforated jaw 19 forwardly in the direction of the fixed wall 16 and will effect the squeezing of the mop material effectively. As this movable jaw closes tightly and under pressure against the perforated plate 16 the spring 36 is tensioned, so when the levers 31 are restored to upright position when pressure is removed from the levers and the movable jaw is restored to normal position the mop may then be extricated from the receptacle with the result that the dirty water expressed out of the mop will enter thru the ports 24, 18a, and 20 and find exit into the compartment A of the tub reserved for dirty water. The mop may then be steeped into the compartment B of the tub containing clean water and is ready for reuse upon the floor. By rotating the cock 36a, the dirty water may be withdrawn thru the spigot 35 and out of the dirty water compartment A.

I do not intend to limit myself to the exact details of construction herein disclosed but claim all variations falling within the purview of the appended claims.

What I desire to claim and secure by Letters Patent is:—

1. In a device as described the combination of a fixed perforated wall, a movable perforated wall pivoted contiguous to the lowermost end of the fixed wall, a spring normally holding the movable wall in open position, parallel side walls flanking the edges of the movable wall, a shaft journaled in the side walls, a plurality of pushers secured upon said shaft, rollers journaled in the pushers bearing at all times upon the movable wall, cranks on said shaft pointing in a direction counter to the pushers, and operating levers connected to the cranks, and a cross rod connected to said operating levers.

2. In a device as described, in combination, a pail, a perforated partition therein, a shaft journaled parallel to said partition, a wringer plate movably mounted facing

6 said partition, pushers fixed on said shaft carrying rollers bearing upon the wringer plate for actuating the closing of the latter against the partition, means for automatically restoring the wringer plate to
10 spaced position after the wringing operation, cranks on said shaft extending in a direction substantially opposite to the pushers diametrically, operating levers connected to said cranks so by depressing said levers the shaft is rotated, and means causing both connecting operating levers to operate in unison.

15 In testimony whereof I have signed my name to this specification.

PETER N. MANCUSO.
